MOP DUST ABSTRACTOR

Frank Abbott Haynes, Chicago, Ill., assignor of
one-half to Winfield S. Williams, Chicago,
Ill.

Application July 28, 1933, Serial No. 682,555

5 Claims. (Cl. 15—15)

The primary object of my invention is a dry mop cleaning device, compact, easily transportable, and highly efficient. This application has a specific reference to a specific class of mops, which are specially devised and applicable to the mop cleaning of large floors in institutional buildings, where bare floors commonly prevail. These mops are narrow elongated bodies with a flexible mopping construction which is intended to cover broad areas. This class of mop may range from a few inches width to a number of feet in length. The handle of such a mop is at substantially right angles to the elongated extent of the mop, and ordinarily attached about the center of the mop. Other objects will appear very clearly to anyone familiar with the art.

The attached drawing illustrates an embodiment of my invention, in which Fig. 1 is an elevation of the device. Fig. 2 is a vertical section elevation of the device. Fig. 3 is a cross section at 3—3 in the direction of the arrows.

As illustrated 10 is an elongated rectangular housing, having a base 10a extending slightly forward of the front of the housing; 11 are a series of cleats vertically spaced around the inner walls of the housing; 12 is a network—preferably wire—attached to the said cleats 11, which cleats space the network 12 from the inner walls of the housing: the cleats 11 and the network 12 extend from a point adjacent the top of the housing down to a point slightly removed from the bottom of the housing; the said network 12 being open at the top and bottom, also a portion of the front to be hereinafter more definitely described. 12a indicates a treatment of the network at a point where the network extends from one vertical cleat on a wall to a vertical cleat on a wall at an adjacent angle. This is devised at each of the corner positions so that the mopping portions of the mop shall come into close proximity at all points for the removal of gathered material from the mops. A cover 13 is hinged to the top of the housing and has shoulders 14 indented around the edges of said cover, adapted to be seated in a complementary recess 14a at the top of the housing and form a closure of the housing. A spring snap 15 is provided to tensionally press against an edge of the cover 13 for temporary holding of the cover in position of closure: 16 is a slide member attached to the cover 13 and the housing 10 to hold the cover 13 in defined position when open. In the front of the housing I provide a slot 17 extending from the top of the housing downwardly to approximately 55 below the center. This slot 17 has attached at

its inner edges a pair of resilient members 18—preferably of rubber composition—their free edges extending into the area of the slot and substantially in edge contact vertically; these elastic members 18 being rigidly held attached at the inner edges of the slot by cleats 19 with attaching members 20: the network 12 being left open adjacent this slot 17, the said opening in the network extending from the top of the network downwardly to the point where the flexible elements terminate. 21 are a series of inclined cleats extending around the base 10a and the inside walls of the housing from the point where the vertical cleats 11 and the network 12 terminate; these cleats 21 are inclined toward a hole 22 in the base 10a of the housing: this hole 22 has a slide 23 normally covering the same adapted to catch the weightier particles of refuse dropping down from the operation of the device and has a handle 23a external of the housing adapted to pull it forward for release of the dirt fallen into the bottom of the chamber of the housing. Hingedly attached to an extension of the base 10a I provide a footboard 24 adapted to swing upward with its edge against the body of the housing for convenient transportation, there being a spring snap arrangement 25 on the face of the housing for frictional temporary holding of the member 24, the purpose of the member 24 being to be let down when the device is standing ready for operation—30 permitting the operator to step upon this member 24 thus giving a certain rigidity to the entire device while he performs his mop cleansing operation hereinafter described. 26 is a wheel functioning in a bracket 27 attached to the back of the housing near the base, one of said wheels and its mounting being located at either side of the base at the rear, the wheel circumference being substantially on a line with the base and so adapted that when the footboard 24 is raised—with 40 the intention of moving the device to a different position—by a slight tilting of the wheels the device is raised from contact with the floor and rendered propellable, a hand hold 42 being provided adjacent the top of the housing externally 45 on the back affording the operator means of tilting the device for easy propulsion on the wheels. 28 is a horizontal slot in the back wall of the housing and some distance removed from the bottom of the base of the machine; and below the 50 said slot 28 are a pair of brackets 29. A gasket 30 with a slot is placed to register with the slot 28 of the housing. A suction machine with its bag 31 and its nozzle portion 32 is removably seated in the bracket 29 with its nozzle aperture 55

registering with the slot in the gasket 30 and the housing slot 18; a strap 33 attached to the housing is adapted to extend around the suction machine housing to hold it tightly in position, the bag 31 being suspendable on a hook 34 on the rear of the housing. An outlet connection 36 is set in the rear of the housing wall having means for receiving the plug connection of the suction machine, and an outlet connection 37 in the upper portion of the rear of the machine is adapted to receive a plug with an electric service. Associated with the outlet member 37 is a switch member 35 so positioned that when the lid 13 is brought down to a closed position in contact with the spring snap 15 a contact is made through the medium of an electric circuit 38 extending between the outlets 36 and 37 so that when the lid is brought down to its closing position the motor of the suction machine 32 is set in motion producing a suction in the chamber of the dry mop machine; and the lifting of the cover 13 breaks the connection; the machine thus operating in suction only when the operator is using it for the operation for which it is constructed. I provide a pair of brackets 39 on a side of the machine spacedly adapted to winding thereon surplus electrical wiring, or electrical service connection, when transporting from place to place, or when set aside for nonuse. The footboard 24 hingedly attached at 40 to the extension of the base 10a is adapted to be operated for the purpose of giving greater rigidity to the whole machine when in operation, the operator stepping upon the board member 24 with one of his feet, ordinarily extending the other to the extension of 10a whereby he steadies the machine for its intended operation.

The purpose of the machine and its operation are as follows:

In the cleaning of large buildings and series of buildings, as in schools, churches, universities, and such like institutions it has become a sanitary procedure to mop the floors with what are called dry mops. These mops are more or less a lengthened type of mop and so devised as to gather dust and dirt from the floors without creating a dust to float in the atmosphere. When the operator has gathered upon his mop what he deems sufficient he steps up to his machine—onto the board and base in the front—and raising his mop to a practically vertical position he inserts one end of the same through the top opening into the encircling network; the handle of the mop being inserted in the slot in contact with the elastic members—hugging the same. When the mop is fully inserted the lid is drawn down which instantly automatically starts a motor in the suction machine which produces a suction within the chamber. Then the operator reciprocatingly raises and lowers his mop, shaking it, the mopping portion of the mop slightly flicking the network walls loosens the dust and dirt from the mop so that the dust particles are taken out through the medium of the suction machine while the heavier particles fall to the bottom of the chamber. This machine can be placed so that a number of mopping operators can use the said machine in as continuous process as may be desired for conserving economy of time and service. The slide covering the hole in the bottom of the machine gives an immediate release to any heavier particles of dirt not easily removed by the suction machine. The device is most economically and conveniently transportable, the simple operation being to detach one

plug, lift the footboard to its locking position, grasps the handle on the back, slightly tilt the machine and propel it like a hand truck to any other desired position.

I do not limit myself to a variation of details only in so far as I am limited in the scope of my claims.

I claim:

1. In a device for cleaning mops of the type described, a vertically elongated housing having a normally closed base with a valve opening therein, and a cover; a vertical slot located in an upper portion of one vertical wall of the housing and communicating with the top opening; flexible members mounted one on either side of the slot contacting each other at their free ends; a vertically positioned elongated foraminous member within the housing chamber spaced apart from the inside walls of the housing, said member consisting of wire of comparatively large open mesh; said foraminous member extending substantially the depth of the housing and following its vertical contour; a slotted wall in the foraminous member registering with the slot in the housing wall and communicating with the open top of the foraminous member providing an unobstructed space between the foraminous member walls and the housing walls.

2. A device for cleaning dry mops of the type described, comprising a narrow vertically elongated housing having a normally closed base and an open top, there being a vertical slot in an upper half of one wall of said housing communicating with the top opening, a closure for the top opening, flexible resilient means mounted in association with the slot to form an automatic flexible closure thereof adapted to form a substantially dust proof housing, a foraminous member consisting of a coarse mesh of metal vertically positioned in said housing and extending the vertical depth of the housing, its walls spaced apart from the walls of the housing, there being a vertical slot in the upper half of one wall of the foraminous chamber registering with the slot in the wall of the housing.

3. In a dust mop cleaner of the type illustrated and described a housing chamber with a vertical network member consisting of wire woven in coarse mesh spaced apart therein providing a space therearound vertically therethru; a slotted wall in one side of the housing and a slotted wall in one side of the network member registering with the slot in the housing; a complementary pair of flexible members, one attached at either side of the slot in the housing and extending toward the other to a point of alignment; an enclosing top to the housing and the network member; a base to the housing including a valve for the release from the chambers of material deposited therein.

4. A mop cleaner of the type described, comprising a vertically elongated housing, including a base and a cover enclosing a primary chamber; a series of spacing members attached to the inner walls of the housing; a vertical network member constructed of wire woven in coarse mesh attached to said spacing members defining a space apart from and parallel with the walls of the housing, the network member being open at the top and bottom; a slot in one of the walls of the network and a slot in one of the walls of the housing registering with the slot in the wall of the network, the slots in the walls of the housing and the network communicating with the opening in the top of the housing; a cover adapted

to close the opening in the top of the housing and the top of the network; an aperture in a wall of the housing adapted to provide communication with an external suction means for the removal from the chamber of dust laden atmosphere.

5. A device for cleaning dry mops of the type described, comprising a housing enclosing a space, a network vertically supported in said 10 chamber said network being constructed of woven wire of coarse mesh and extending the depth of the housing chamber and defining a secondary chamber whose walls are parallel to the walls of the housing and spaced apart therefrom there 15 being a slot portion in the upper half of one wall

of the housing and a slot in a wall of the network registering with the slot in the housing whereby a mop with a handle may be inserted in the space enclosed by the network and be vertically manipulated therein by the handle from an external position through the slots in the registering walls of the network and the housing, means to close the top of the housing when the mop is inserted there being means external of the housing 10 and communicating with the chamber of the housing adapted to produce and sustain a suction in the housing while the mop is being cleansed.
